UNITED STATES PATENT OFFICE

WILLIAM A. OLSON, OF PACIFIC, MISSOURI

CLAMSHELL BUCKET

Application filed December 20, 1932. Serial No. 648,111.

This invention relates to improvements in clam shell buckets, the general object of the invention being to provide means whereby the bucket can be easily and quickly opened and closed and whereby the weight of the bucket is used to open it and means whereby the bucket can be closed at different speeds by different arrangements of the closing cable on the pulleys or sheaves.

10 This invention also consists in certain other features of construction and in the combination and arrangement of the several parts to be hereinafter fully described illustrated in the accompanying drawings and specifically 15 pointed out in the appended claims.

In describing the invention in detail, reference will be had to the accompanying drawings wherein like characters denote like or corresponding parts throughout the several 20 views, and in which:—

Figure 1 is an elevation of the improved bucket showing the bucket in closed position in full lines and in open position in dotted lines.

25 Fig. 2 is a vertical sectional view through Fig. 1.

Fig. 3 is a vertical sectional view through Fig. 2.

Fig. 4 is a section on line 4—4 of Fig. 2 30 looking in the direction of the arrows.

Fig. 5 is a section on line 5—5 of Fig. 2 looking in the direction of the arrows.

Fig. 6 is a section on line 6—6 of Fig. 2.

Fig. 7 is a view of one of the lower pulley 35 supporting members.

Fig. 8 is a detail view showing the upper part of one of the frame members.

Fig. 9 is a detail view showing how a cable anchor is attached to a supporting bar.

40 In these drawings, the letter A indicates the bucket which is composed of the sections 1 and 2 and a pair of upwardly extending members 3 have their lower ends connected to the top part of each section as shown at 4, 45 A long bolt 5 passes through the intermediate

part of the two pairs of members 3 with said members of one pair crossing diagonally the members of the other pair as shown.

A pair of sheaves or pulleys 7 and 8 are rotatably arranged on the bolt 5 and are 50 held in the position shown in Fig. 3 by the spacers 9. An inwardly extending arm 10 is fastened to the upper end of each of the members 3 and is connected by a brace 11 with another part of each member 3. A bolt 55 12 passes through the arms and braces of each pair of members 3 and supports a pair of pulleys 13 which are held in the position shown in Fig. 3 by the spacers 14.

Cable anchors 15 are also placed on the 60 bolts one at each side of the pair of pulleys and each pair of pulleys is provided with an arcuate-shaped cable guide 16. Each of the pulleys 7 and 8 is provided with a cable guide 17 and a pulley 18 has its shaft 19 supported between the members 3 of each pair of members by the brackets 20 having their bent outer ends connected with the lower ends of the members 3 and their inner ends bent upwardly and perforated as shown at 70 21 to receive the ends of the shaft 19.

Each pulley 18 is also provided with a cable guide 22. A cable 23 has one end attached to one of the anchors 15 with the cable passing over one of the pulleys 13 of one set 75 and then under a pulley 13 of the other set and leads to suitable control means so that when this cable is pulled upon the two sections of the bucket are moved to closed position as shown in Fig. 1.

If the closing action of the bucket is to be changed, the cable 23 can be passed around the other pulley 13 of the two sets. A cable 24 is connected to an anchor 25 carried by one of the bolts 12 and said cable passes downwardly over a pulley 18 on the section 2 and then passes upwardly over the pulley 8 and has its upper end connected to a cross piece 26 attached to a control member 27. Another cable 28 is attached to an anchor 29 80 85 90

connected with the other bolt 12 and passes downwardly and under the pulley 22 of the section 1 and then upwardly over the pulley 7 and the upper end of this cable 8 is attached 5 to the cross piece 26.

Thus by raising the member 27 to raise the cross piece, both cables 24 and 28 will be pulled upon and thus the two sections 1 and 10 2 of the bucket will be swung to open position. The cable guides will prevent the cables from jumping off the pulleys or sheaves and brackets 29' can be attached to all four corners of the bucket for the tag lines.

As will be seen, all working parts are on 15 top of the bucket and there are no corner working parts which eliminates wear on bucket corners, and by providing large pulleys or sheaves, cable wear is reduced to a minimum.

20 It is thought from the foregoing description that the advantages and novel features of the invention will be readily apparent.

It is to be understood that changes may 25 be made in the construction and in the combination and arrangement of the several parts provided that such changes fall within the scope of the appended claims.

Having thus described my invention, what 30 I claim as new is:—

35 1. In a clam bucket of the class described composed of two sections, upright members crossing each other and arranged in pairs, one pair being connected to the top part of one section and the other pair to the top part of the other section, a pivotal member passing through the members where they cross each other, inwardly extending parts at the upper ends of the two sets of members, shafts passing through said inwardly extending members, pulleys carried by the shafts, a cable connected to one inwardly extending member and passing over certain pulleys of the two sets for closing the sections of the bucket, pulleys connected with the upper 40 portions of the two sections, pulleys carried by the centrally arranged pivotal member, cables passing over the last-mentioned pulleys and under the pulleys carried by the sections and having their upper ends connected with the inwardly extending portions of the tops of the upwardly extending members.

45 2. In a clam bucket of the class described composed of two sections, upright members crossing each other and arranged in pairs, one pair being connected to the top part of one section and the other pair to the top part of the other section, a pivotal member passing through the members where they cross each other, inwardly extending parts at the upper ends of the two sets of members, shafts passing through said inwardly extending members, pulleys carried by the shafts, a cable connected to one inwardly extending member and passing over certain pulleys of

the two sets for closing the sections of the bucket, pulleys connected with the upper portions of the two sections, pulleys carried by the centrally arranged pivotal member, cables passing over the last-mentioned pulleys and under the pulleys carried by the sections and having their upper ends connected with the inwardly extending portions of the tops of the upwardly extending members, and means associated with the pulleys for preventing the cables from jumping therefrom.

70 75 In testimony whereof I affix my signature.

WILLIAM A. OLSON.
